UNITED STATES PATENT OFFICE.

ROBERT B. DYER, OF WAURIKA, OKLAHOMA.

CALENDAR.

1,251,195.

Specification of Letters Patent. Patented Dec. 25, 1917.

Application filed March 12, 1917. Serial No. 154,291.

To all whom it may concern:

Be it known that I, ROBERT B. DYER, a citizen of the United States, residing at Waurika, in the county of Jefferson and State of Oklahoma, have invented certain new and useful Improvements in Calendars; and I do declare the following to be a full, clear, and exact description of the invention, such as will enable others skilled in the art to which it appertains to make and use the same.

My invention relates to improvements in calendars and more particularly to that class in which the card bearing the numbers of the days of the month is adjustable in an envelop having an opening therein through which the numbers may be viewed.

Another object of this invention is to provide a calendar which may be used year after year by merely changing the year number, and monthly shifting or adjusting the card bearing the numbers of the days of the month in an envelop having an opening therein through which said numbers may be viewed.

A still further object is to provide a calendar to be used year after year and having a rotatable disk carrying the names of the months of the year on its periphery and adapted to be viewed through a small opening in an envelop in which the disk is mounted.

With these and numerous other objects in view the invention consists of the construction and arrangement of the several parts, as will be more fully hereinafter described and claimed.

In the accompanying drawings in which Figure 1 is a front elevation of the calendar;

Fig. 2 is a vertical section on the line 2—2 of Fig. 1;

Fig. 3 is a front elevation of the cards which are inserted in the envelop;

Fig. 4 is a front elevation of one of the insertible cards;

Fig. 5 is a front elevation of another insertible card;

Fig. 6 is a front elevation of a third insertible card;

Fig. 7 is a front elevation of the rotatable disk bearing the names of the months of the year.

Similar numerals of reference indicate corresponding parts in the several views.

In constructing my calendar I provide a

card receiving envelop or frame 1 having its upper end open for the insertion of a card bearing the days of the month and other necessary information, said envelop or frame 60 having a comparatively large rectangular opening 2 in its front face 3 for a purpose to be hereinafter set forth. The envelop is provided at points spaced above the opposite upper corners of the large opening 2 with 65 rectangular spaces 4 and 5 for the purpose of receiving the number of the year, the first two numbers being shown in the space 4 on the left hand side of the envelop and the last two numbers of the year in the space 5 on 70 the right hand side.

At a point substantially midway the distance between the upper edge of the large opening 2 and the upper edge of the envelop 1 a disk 6 is rotatably mounted, said disk 75 having its center or axis 7 positioned midway between the side edges of said envelop, the disk being disposed between the two flat faces of said envelop. Around the disk near its periphery are positioned in spaced relation the names of the months of the year to be viewed through the small rectangular opening 8 disposed midway between the spaces 4 and 5 bearing the number of the year and spaced above the large rectangular 85 opening 2.

The envelop or frame 1 is provided adjacent the left side of the large rectangular opening 2 with the names of the days of the week vertically alined in horizontal spaces 90 9 beginning with Sunday in the upper space, Monday in the second space, etc., continuing seven spaces and on the opposite side of the large opening with the numbers of the days of the week as shown in Fig. 1 of the 95 drawings.

The portions to be inserted comprise a card 10 of a size to snugly fit in the envelop, said card having the names of six days of the week (excluding Sunday) vertically 100 spaced in horizontal spaces 11 at the upper end and whose purpose will be hereinafter set forth; a second rectangular card 12 of such dimensions as to cover the entire space below the aforesaid horizontal spaces when 105 in its lowermost position and having arranged in vertical and horizontal spaces the numbers of the days of the month as shown and a third card 13 substantially L-shaped whose purpose will be hereinafter described. 110 These three cards are held together by spring clips 14 or other suitable elements

and are relatively adjustable as will be hereinafter set forth.

The operation of the calendar is as follows:

- 5 Should the first day of the month fall on Thursday the card 12 bearing the numbers of the days of the month is moved upwardly on the other card 10 which snugly fits in the envelop. When the name Thursday in one 10 of the horizontal spaces on the other card appears adjacent the upper edge of the card 12 bearing the numbers of the days of the month the upward movement is stopped.
- 15 The L-shaped card 13 is shifted vertically on the face of the card 12 if the month contains less than thirty-one days. In the drawings the month of February is shown containing twenty-eight days, therefore the L-shaped card 13 is used to cover the numbers 20 twenty-nine, thirty and thirty-one. When the card is inserted in the envelop the first of the month will appear opposite the day Thursday in the column adjacent the side of the large opening 2 as shown in the drawings.

25 The spaces above and below the large opening 2 on the face of the envelop may be utilized for any suitable advertising matter such as stores and real estate offices place 30 on calendars distributed by them in their advertising.

35 From the foregoing description of the construction and operation of my improved calendar, the manner of using the same and the operation thereof will be readily understood, and it will be seen that I have provided a simple and efficient device of this character for carrying out the objects of the invention.

40 I claim as my invention:

1. A calendar comprising an envelop having an open end and a rectangular opening in its front face, names of the days of the week in a vertical column adjacent one side 45 of said opening, a card insertible in said envelop, names of six days of the week vertically arranged in horizontal spaces at the upper end of the card and adapted to be covered by the face of the envelop above said 50 opening, a second card covering the entire

space below the names of the six days of the week and slidably contacting the front face of the aforesaid card, said second card having numbers and the days of the month arranged in vertical and horizontal spaces, 55 said second card having the numbers arranged so that when it is moved vertically to cover one or more of the names of the days of the week on the first named card the name of the day appearing adjacent its 60 upper edge will correspond with the name of the day of the week appearing opposite the first day of the month on said second card.

2. A calendar comprising an envelop having an open top and a rectangular opening in its front face, names of the days of the week in a vertical column adjacent one side of the opening, a card insertible in said envelop, names of six days of the week vertically arranged in horizontal spaces at the upper end of the card and adapted to be covered by the face of the envelop above the opening, a second card covering the entire space below the names of the six days of the week and slidably contacting the front face of the aforesaid card, said second card having the numbers of the days of the month arranged in vertical and horizontal spaces and having the numbers arranged so that 75 when it is moved vertically in relation to the first named card to cover one or more of the names of the days of the week on the first named card the name of the day appearing adjacent its upper edge will correspond with the name of the day of the week appearing opposite the first day of the month on said second card, and a substantially L-shaped card shiftable on the second named card to cover up a portion of the numbers 80 when there are less than thirty-one days in the month.

In testimony whereof I have hereunto set my hand in the presence of two subscribing witnesses.

ROBERT B. DYER.
